ATTORNEY

UNITED STATES PATENT OFFICE.

EVERETT F. DAILEY, OF ST. LOUIS, MISSOURI, ASSIGNOR TO MERCHANTS CHEMICAL COMPANY, OF ST. LOUIS, MISSOURI, A CORPORATION OF ILLINOIS.

ANCHORING BAR FOR CURTAIN STRETCHERS.

Application filed January 5, 1923. Serial No. 610,819.

To all whom it may concern:

Be it known that I, EVERETT F. DAILEY, a citizen of the United States, residing in the city of Saint Louis and State of Missouri, have invented new and useful Improvements in Anchoring Bars for Curtain Stretchers, of which the following is a specification.

This invention relates to curtain-stretchers of the type shown in the patent to Lockwood No. 1,142,823, and has for its object to provide an improvement in the means for anchoring one end of the curtain, which is secured at its opposite end and at its sides on brushes provided in channel bars at opposite sides and at one end of the stretcher frame. In the patent referred to, the means illustrated and described for this purpose is a rod which is inserted through the terminal loop, or hem, of the curtain, the opposite ends of the rod being inserted in openings in the vertical flanges of the side angle bars of the frame, this rod being usually relatively thin, so that it can be readily inserted in the said loop or hem of the curtain. A second brace rod is employed which is also inserted in the holes in the side angle bars and coupled to the first rod by a catch, or hook.

In practice, it has been found that the operation of stringing the wet hem of the curtain over the rod is quite troublesome and requires considerable time, and additional trouble and time is involved in placing the two rods in the proper holes and inserting pins, or the like, in the ends of the rod to prevent their accidental withdrawal.

Furthermore, a great many curtains have no hem at the end, and the securing of the end of such a curtain with the rod shown in said patent presents still further difficulties.

To overcome these objections, I have devised the anchoring device forming the subject matter of this invention. This device comprises a channel bar provided with brushes on its upper side, the ends of the channel bar having projections, one at one end and two at the other, for engaging in suitable openings in the angle bars at the sides of

the frame, and resilient means, such as a spring, being provided at one end of the channel bar to hold the same in position after the projection at that end of the bar has been inserted in an opening at that side 55 of the frame against the resistance of the spring, and the two projections at the opposite ends of the bar have been inserted in suitable openings in the opposite side of the frame. By this means, the bar can be rapidly 60 adjusted to the proper position in the frame, and it is only necessary to stretch the terminal end of the curtain and place it on the brushes in the bar to anchor it in position.

In the accompanying drawing,

Figure 1 is a broken plan view of a curtain-stretcher, showing my improved anchoring bar in position;

Figure 2 is a broken plan view on an enlarged scale to illustrate the construction and mode of application of the bar to the side bars of the stretcher frame;

Figure 3 is a longitudinal sectional view of the construction shown in Figure 2; and

Figure 4 is a cross-section on the line 4-4 of Figure 2.

Referring now to the drawing, the numeral 1 indicates a box or casing, preferably of sheet metal, forming a hot air chamber 80 and provided at its bottom with a steam coil 2 for heating it, as described in the Letters Patent aforesaid. At the top of the casing 1 is rotatably mounted the stretcher 3, which comprises a double open rectangular frame, 85 each member of which comprises side angle bars 4 and end angle bars 5. Extending along and secured to one of the side bars 4 is a channel bar 6 provided with brushes 7, and extending along and secured to one 90 of the end angle bars 5 is a channel bar 8 provided with brushes 9. Extending between the two side angle bars 4 of the frame are rods 10, on which is adjustably mounted a third channel bar 11 provided with 95 brushes 12, the channel bar 11 having sleeves 13 sliding over the rods 10, which are provided with binding screws 14 clamping the channel bar in any adjusting position on the rods 10. The double frame, as a whole, is 100

mounted on trunnions 15, mounted in suitable bearings in opposite ends of the casing 1. Only one of the stretcher frames has been described as the other is an exact duplicate and the application of my invention to each is the same.

In applying a curtain to the stretcher frame, one side of the curtain is placed over the brushes 7 and one end over the brushes 9 of the respective channel bars 6 and 8, and the remaining side of the curtain is placed on the brushes 12 of the channel bar 11, which is then moved outward over the rods 10 to stretch the curtain, and locked in an adjusted position by screwing down screws 14 into engagement with said rods. The opposite end of the curtain is then anchored by the device which I will now describe.

Referring to Figures 2, 3 and 4, the numeral 16 indicates a channel bar which is provided with brushes 17, the latter, as a whole, comprising a base of cloth, or the like, 18 having wire staples inserted through its bottom and projecting from its top. The channel in the bar 16 is provided by bending over its opposite edge portions, as indicated at 19, and the cloth 18 is inserted into the channel from one end of the bar with its opposite edges engaging under the channel members 19, as shown in Figure 4; the channel members 19 are then bent into binding engagement with the cloth. At one end of the bar 16, I provide two longitudinal parallel projections, or pins, 20, one at either side of the bar, for insertion in openings in the vertical flange 21 of one of the side bars 4 of the frame. At the opposite end of the bar, I provide a pin 22 which is considerably longer than the pins 20. The pin 22 is provided on the end of a plate 23 which is applied to the bottom of the channel bar 16 at the end, as shown by Figure 3, and secured thereon by a clip 24, which is riveted, or otherwise secured to the bar at its inner end, as indicated at 25, and is bent to extend over the plate 23 and to have a rivet 26 pass through it and said plate and to be secured in the back of the channel bar. Encircling the pin 22 and suitably secured at its inner end in position thereon, is a coil spring 27, the outer end of which is free. The vertical flange of one of the bars 4, as stated, is provided with a series of apertures for receiving the pins 20, these apertures being represented by dotted lines in Figure 2 and indicated by the numeral 28, and the vertical flange 29 of the other side bar 4 is provided with a series of apertures for receiving the pin 22, which apertures are also represented by dotted lines in Figure 2 and indicated by the numeral 30.

In operation, the curtain having been anchored at its ends and two sides as described, the free or terminal end of the curtain is engaged over the brushes 17 and the bar

pulled outward to stretch the curtain, and then inserted in the appropriate apertures 28 and 30. To do this, the pin 22 is first inserted in the aperture 30 and the bar pressed toward the flange 29 against resistance of spring 27. This permits the pins 20 to be brought opposite the appropriate openings 28, when, by releasing pressure on the bar, the spring 27 will force the pins 20 into said openings, and, being interposed between the opposite angle bar 4 and the end of the channel bar 16, will constantly exert pressure on the bar to keep the pins 20 from being accidentally withdrawn from the openings. The pin 22 is sufficiently long, as will be understood, to remain in engagement with the opening 30 after the pins 20 have been forced into their openings by the spring 27. The provision of the two pins 20 is, of course, for the purpose of preventing the bar 16 from turning, after once being positioned in the frame. Another way of manipulating the bar would be to place it in position in the frame in the manner last described adjacent to the terminal end of the curtain, and then stretch the curtain by hand and place it in engagement with the brushes 17.

It will be obvious that changes could be made in the construction shown and described herein without departing from the spirit of my invention. For example, it is clear that the spring could be placed at the opposite end of the bar from that shown, and that the two pins at this end of the bar could be made longer than the single pin at the opposite end. Also, it will be equally obvious that both ends of the bar could have two pins. As these are not modifications of the invention, but mere alternative constructions, I have not considered it necessary to illustrate the same, as a mere reference is sufficient to indicate that they are included within the scope of my invention, as outlined in the claims.

I claim:

1. In combination with a curtain-stretcher frame having parallel side bars provided with a series of openings, means for anchoring the terminal end of a curtain, comprising a bar having a pair of pins at one end for engaging in the openings of one bar, and a pin at its opposite end for engaging in the openings of the other bar, resilient means at one end of the bar against the resistance of which the said pair of pins are inserted into their openings after the said single pin has been inserted in its opening, and means on the bar for engaging the terminal end of the curtain to hold it in a stretched condition.

2. A device for use in curtain-stretchers, comprising a bar having a plurality of pins projecting from one end, and a single pin projecting from the other end, a coil spring

secured to one end of the bar, and means on said bar for engaging the end of a curtain to be stretched.

3. A device for use in curtain-stretchers, comprising a bar having a pair of pins projecting from one end, and a single pin projecting from the other, a brush secured on

one side of said bar for engaging the end of a curtain, and a coil spring secured at one end to said bar and encircling said single pin.

In testimony whereof, I have hereunto set my hand.

EVERETT F. DAILEY.
